UNITED STATES PATENT OFFICE.

ARTHUR J. CULP, OF CLANTON, ALABAMA.

EXHAUST TRAP.

Application filed October 25, 1923. Serial No. 670,745.

To all whom it may concern:

Be it known that I, ARTHUR J. CULP, a citizen of the United States, residing at Clanton, in the county of Chilton and State 5 of Alabama, have invented certain new and useful Improvements in Exhaust Traps; and I do hereby declare the following to be a full, clear, and exact description of the invention, such as will enable others skilled 10 in the art to which it appertains to make and use the same.

The invention provides a trap to muffle the exhaust of a gas engine and shrink the same so as to create a vacuum to make a 15 forward pull on the piston when the exhaust port opens.

A further purpose of the invention is the provision of efficient means for the smoke stack of a locomotive engine to catch and 20 control the soot and cinders and deaden the sound of the heavy exhaust.

The invention also aims to provide means for stove flues, chimneys and smoke stacks to be applied to the top thereof as a protection 25 against fire and to catch and control the soot, cinders and sparks.

Other objects and advantages will be apparent and suggest themselves as the nature of the invention is understood.

30 While the drawings illustrate an embodiment of the invention it is to be understood that in adapting the same to meet different conditions and requirements, various changes in the form, proportion and minor details 35 of construction may be resorted to without departing from the nature of the invention.

Referring to the accompanying drawings forming a part of the application:

Figure 1 is a vertical central sectional 40 view of an exhaust trap embodying the invention,

Figure 2 is a horizontal sectional view on the line 2—2 of Figure 1, and

Figure 3 is a view of the check valve as 45 seen from the bottom side.

Corresponding and like parts are referred to in the following description and designated in the several views of the drawings by like reference characters.

50 The device comprises similar headers 1 and 2 and a plurality of cooperating tubes. The headers 1 and 2 are hollow and of semi-spherical form, the flat sides having openings formed therein to register with cooperating tubes. The center portion of the flat

side of the header 1 is closed, as indicated at 3, and the outer portion is provided with a plurality of openings 4. The center portion of the flat side of the header 2 is formed with an opening 5 and its outer portion is 60 provided with openings 6 to correspond with the openings 4 in the flat side of the header 1. Tubes 7 connect the openings 4 and 6 of the headers 1 and 2. A centrally disposed tube 8 is clamped between the flat 65 sides of the headers 1 and 2 and is closed at its upper end by the solid portion 3 of the header 1 and its lower end is in register with the opening 5 of the header 2. Annular centering flanges 9 are formed upon 70 the opposing sides of the headers 1 and 2 to receive the ends of the several tubes to retain them in place and insure a close joint. Each of the headers has outer flanges 10 in which are formed openings to receive tie 75 bolts 11 whereby the headers are connected and the tubes clamped therebetween. The space 12 of the header 1 constitutes a vacuum chamber and the space 13 of the header 2 a trap to catch soot, cinders and sparks. 80 A tube 14 connects centrally with the semi-spherical shell of the header 2 and passes through the space 13, opening 5 and center tube 8 and terminates a short distance from the flat side of the header 1. The tube 14 85 is of less diameter than the tube 8 and is spaced therefrom. The exhaust, smoke and the like is supplied to the lower end of the tube 14.

A blow-off pipe 15 connects with the header 2 and is provided with a lever gate valve 16 which may be operated from a convenient point by means of a cord, not shown, or other connection, whereby soot, cinders or other accumulation may be blown 95 from the chamber 13 between stations without requiring stopping of the train. A check valve is provided centrally of the semispherical shell of the header 1 and comprises a casing including a lower semi-spherical portion 16 and an upper constricted portion 17 terminating in a collar 18. A valve member 19 is located within the semispherical portion 16 of the casing and preferably consists of a disk of aluminum 100 bent into concavo-convex form to obtain a snug seat upon the inner lower side of the casing. A nipple 20 connects the valve casing with the header 1 and may constitute 105 a part of either or be separate therefrom. A 110

combined guide and stop 21 pendent from the valve member 19 extends through the nipple 20 and coacts with a ring 22 within the nipple 20 to give proper direction to 5 the valve in its seating and unseating. The member 21 consists of a plurality of elements grouped about a central line and having their lower ends outwardly deflected to engage the lower end of the nipple 20 and 10 limit the unseating of the valve.

The device is adapted to be coupled to a stack, pipe or other part by means of the tube 14 and the exhaust may discharge directly from the outlet of the check valve 15 or through a pipe which may be coupled to the collar 18 thereof. The several tubes 7, 8 and 14 are preferably of sheet metal, whereby to cool the exhaust, smoke or the like passing therethrough, whereby to create 20 a vacuum within the device which exerts a pull on the piston when the exhaust port opens.

In applying or adapting the trap to a gas engine with more than one cylinder, it is 25 necessary to provide a trap for each cylinder and conduct the exhaust therefrom to the trap whereby to provide for the vacuum to operate in the manner stated.

What is claimed is:

- 30 1. A device of the character specified, comprising spaced headers, each header having corresponding openings in its outer portion and one header having its central portion solid and the opposite header having an opening in its central portion, tubes connecting the outer openings of the headers, a central tube closed at one end by a header and in communication at its opposite end with the central opening of the opposite 35 header, a tube connected with the last mentioned header and extending through the opening thereof and into the central tube and terminating a short distance from the closed end thereof, and a check valve applied to the header serving to close the end 40 of the center tube.
- 45

2. A device of the character specified, comprising spaced headers, each header having corresponding openings in its outer portion and one header having its central portion solid and the opposite header having an opening in its central portion, tubes connecting the outer openings of the headers, a central tube closed at one end by a header and in communication at its opposite end with the central opening of the opposite header, a tube connected with the last mentioned header and extending through the opening thereof and into the central tube and terminating a short distance from the closed end thereof, and a check valve applied to the header serving to close the end of the center tube, said check valve comprising a casing including a semispherical portion and a cooperating valve member having its seating face convex to close against the inner side of the semispherical portion of the casing, and combined guide and stop means cooperating with the valve member. 55

3. A device of the character specified, comprising similar semispherical headers having corresponding openings in the outer portion of their flat sides, one header having the center portion of its flat side solid and the other header having an opening in 75 the center of its flat side, a center tube closed at one end by the header and in communication at its opposite end with the other header, a tube connected to the latter and extending into the center tube and terminating a short distance from its closed end, means connecting the headers and clamping the tubes therebetween, a check valve applied to the vacuum header, and a blow-off pipe applied to the trap header. 80

In testimony whereof I affix my signature in presence of two witnesses.

ARTHUR J. CULP.
